PRODUCTION OF LONG CHAIN ALKYL SUBSTITUTED AROMATIC HYDROCARBONS

Robert A. Sanford, Park Forest, and Bernard S. Friedman, Chicago, Ill., assignors to Sinclair Refining Company, New York, N. Y., a corporation of Maine

No Drawing. Application April 1, 1954,
Serial No. 420,446

4 Claims. (Cl. 260—671)

Our invention relates to the production of long chain alkyl substituted aromatic hydrocarbons which have particular value in the production of oxidation-stable alkyl aromatic acids and detergent compositions. More particularly, our invention relates to the production of such alkyl aromatics in which the alkyl group contains at least 8 carbon atoms by the alkylation of aromatic hydrocarbons with scission-susceptible olefins in the presence of aluminum halide catalysts.

Long chain alkyl aromatic hydrocarbons are conventionally produced by the alkylation of an aromatic hydrocarbon, e. g. benzene, in the presence of an alkylation catalyst such as aluminum chloride. When the alkylation is carried out with a straight chain olefin, the olefin remains intact and the desired long chain alkyl aromatic hydrocarbon is produced with no difficulty. Scission-susceptible polyolefins, such as diisobutylene, may also be used to react with more reactive aromatic nuclei such as phenol to produce long chain alkyl aromatics. When, however, the scission-susceptible olefins are reacted with monocyclic aromatic hydrocarbons such as benzene or toluene, the olefin apparently undergoes extensive polymerization and depolymerization or cleavage prior to alkylation and the resulting product is a mixture of alkyl aromatic hydrocarbons containing new side chains both lower and higher in aliphatic molecular weight than the olefin originally used. This degradation of the olefin also results in the production of substantially inseparable poly-alkylated aromatics of the same molecular weight and boiling range as the desired alkyl aromatic. For example, when benzene is alkylated with diisobutylene under normal alkylation conditions, the olefin appears to undergo depolymerization prior to alkylation and the final product consists mainly of short chain mono- and di-tertiary butylated benzene rather than long chain octylated benzene. This is very undesirable, as sulfonation of this mixture produces low yields of sulfonates which are poor in detergent quality and which require costly purification to eliminate or reduce odor, unsulfonated residue and color bodies. Because of this difficulty, processes dealing with the production of long chain alkyl aromatics for detergent manufacture by the alkylation of aromatics with an olefin specify that the olefin be substantially free from scission-susceptible olefins such as isobutylene polymers or copolymers.

We have now found that valuable long chain alkyl substituted monocyclic aromatic hydrocarbons in which the alkyl group contains at least 8 carbon atoms are produced in good yields by the alkylation of the aromatic hydrocarbon with scission-susceptible olefins containing at least 8 carbon atoms in the presence of catalysts comprising aluminum halides by controlling the temperature between about -65 to -15° C. By controlling the temperature sufficiently low, cleavage of the olefin is avoided. Thus, toluene is octylated or dodecylated with diisobutylene or triisobutylene respectively, or select cleavage-alkylation occurs resulting in the production of alkyl aromatics

2

tics in which the alkyl group contains at least 8 carbon atoms, for example, octylation of toluene with tetraisobutylene. Undesirable cleavage resulting in the formation of short chain butylated products is substantially avoided and formation of undesirable short chain and polymer products is kept to a minimum.

According to our invention, a monocyclic aromatic hydrocarbon is reacted with a scission-susceptible olefin in the presence of a catalyst comprising aluminum halide while controlling the temperature between about -65 to -15° C. At higher temperatures, excessive butylation occurs and at lower temperatures excessive polymerization occurs with little intact alkylation. The reaction is stopped, for example, by quenching with water, the product is washed with water or alkali solution, dried and the products recovered by distillation.

Generally, the catalyst and aromatic are mixed and then contacted with the olefin. The manner of contacting is important in that abnormal orientation and cleavage reactions may occur with alkylation products while the addition of the olefin to the catalyst and aromatic mixture is being completed. We have found that keeping the olefin concentration low during alkylation and keeping additional contact time after olefin addition to a minimum avoids abnormal orientation and cleavage reactions and results in the production of high yields of the desired alkyl aromatic. Thus, slow addition of the olefin with early quenching of the reaction is preferred procedure. Advantageously, two streams, one containing aromatic hydrocarbon and the olefin and the other aromatic hydrocarbon and catalyst, are directed into a mixing chamber and after a short contact time discharged into a stream of water to stop the reaction. Commercially, a suspended catalyst can be employed and the catalyst separated just before quenching by gravity separation or centrifugation and recycled. The molar ratio of aromatic to olefin to catalyst may vary from about 4-6:0.5-1.5:0.08-0.3. Preferably, the ratio is 5:1:0.1.

By the process of our invention, readily available scission-susceptible olefins can be employed as the olefin source without losses and complications previously encountered in alkylation reactions with aromatic hydrocarbons because of cleavage reactions, to produce, selectively, valuable alkylated aromatics, some of which are novel compounds. The novel compounds produced by our invention are tertiary-alkylated monocyclic aromatic hydrocarbons, i. e. benzene and saturated hydrocarbon substituted benzenes, in which the tertiary-alkyl radical is of a particular type and which contains at least 8 carbon atoms, particularly from 8 to 20 carbon atoms. The tertiary-alkyl radical of our novel compounds is a radical in which all methylene ($-\text{CH}_2-$) or methinyl

groups are attached to at least two quaternary carbon atoms.

The novel compounds include, for example, tertiary-alkylated benzenes such as t-dodecyl-benzene or 2,2,4,6,6-pentamethyl-4-phenylheptane; tertiary-alkylated toluenes such as t-octyl-toluenes or para- or meta-(1,1,3,3-tetramethylbutyl) toluenes, t-dodecyl-toluenes or 2,2,4,6,6-pentamethyl-4-(para- or meta-tolyl) heptanes, t-hexadecyl-toluenes or 2,2,4,6,6,8,8-heptamethyl-4-(para- or meta-tolyl) nonanes; tertiary-alkylated dimethylbenzenes such as dimethyl-(t-dodecyl)-benzenes or 2,2,4,6,6-penta-methyl-4-(3,4- or 3,5-dimethylphenyl)-heptanes, dimethyl-(t-hexadecyl)-benzenes or 2,2,4,6,6,8,8-heptamethyl-4-(3,4- or 3,5-dimethylphenyl)-nonanes; tertiary-alkylated octyl toluenes such as di-t-octyl-toluene or di-(1,1,3,3-tetramethylbutyl)-toluene; and tertiary-alkylated octyl benzenes such as 1,4-di-(t-octyl)-benzene or 1,4-di-

(1,1,3,3-tetramethylbutyl)-benzene. By our invention not only one but two or more of long chain alkyl groups such as t-octyl, t-dodecyl and t-hexadecyl can be attached to aromatic hydrocarbons. Cleavage resulting in undesirable butylated products is kept to a minimum and a minimum of polymer is produced.

The alkyl aromatics are useful as such or as chemical intermediates in the production of other useful compounds. The tertiary-alkylated aromatics are particularly useful for the production of oxidation-stable alkyl aromatic acids. Because of the resistance of the particular type of tertiary-alkyl substituent, tertiary-alkylated saturated hydrocarbon substituted benzenes such as toluene or xylene can be oxidized selectively at the alkyl or cycloalkyl substituents to produce oxidation-stable tertiary-alkylated trimesic, phthalic or benzoic acids useful in greases and, when esterified, in plasticizers and resins. The structure of the tertiary-alkyl group of our novel compounds provides advantageous oxidation resistance in that all methylene or methinyl groups are attached to at least two quaternary carbon atoms. For example, the tertiary groups in the tertiary-octyl and tertiary-nonyl aromatics of our invention have the following structure:

and

Thus, the normally vulnerable position *s* in the methylene group of the tertiary-octyl radical and position *ss* in the methinyl group of the tertiary-nonyl radical are protected by the adjacent quaternary groups which effectively prevent attack by oxidative reagents by virtue of their bulk, involving steric or spatial hindrance.

In contrast, tertiary-alkyl groups of tertiary-alkylated aromatics in which the group contains exposed secondary hydrogens (+) in methylene groups and exposed tertiary hydrogens (++) in methinyl groups, are subject to oxidative attack. For example, the following tertiary-alkylated aromatics are subject to oxidative attack:

and

The aromatics are also useful, for example, in the electrical field where thermal and oxidation stability requirements are critical, for example, as transformer oils, or as a base for highly oxidation-resistant fluids, for example, brake-fluids, and grease lubricants or as plasticizers. Also, the aromatics provide hitherto unavailable alkylated aromatics for sulfonation to produce detergents, wetting agents and emulsifying agents, including synthetic oil-soluble sulfonates. In addition, nitration and reduction of these aromatics yield useful amines for surfactive agents and inhibitors.

By scission-susceptible olefins, we mean olefins, or their hydrogen halide addition products, containing at least 8 carbon atoms which tend to undergo cleavage under normal alkylation conditions. The most useful scission-susceptible olefins contain from 8 to 20 carbon atoms. Examples of such olefins include polymers of

isobutylene, for example, diisobutylene, triisobutylene and tetraisobutylene, polymers of isoamylene, isohexylene and isoheptylene as well as co-polymers of isobutylene with propylene, n-butylene or amylene, and their hydrogen halide adducts. The ease of alkylation without undesirable cleavage varies with the molecular weight of the olefin. Thus, alkylation without undesirable cleavage is more difficult with the higher molecular weight olefins than with diisobutylene, for example, but such alkylation can be effected.

By monocyclic aromatic hydrocarbons, useful for alkylation according to the process of our invention, we mean benzene and saturated hydrocarbon substituted benzenes, i. e. alkyl and cycloalkyl substituted benzenes preferably containing not more than 12 carbon atoms in the alkyl or cycloalkyl group. For example, toluene, butylbenzene, cyclohexylbenzene, octylbenzene, dimethylbenzene, (1-methylcyclopentyl)benzene, cyclohexyltoluene, octyltoluene, and (1-methylcyclopentyl)toluene are useful substituted benzenes. The ease of alkylation varies with the type of substitution in the benzene ring, usually decreasing in reactivity, for example, in the following order: xylene, toluene, benzene, butylbenzene and octylbenzene.

By aluminum halide catalysts, we mean aluminum chloride or aluminum bromide, either unpromoted or promoted by the addition of the corresponding hydrogen halide. Aluminum halide-hydrocarbon complexes such as that formed in the alkylation process, or produced separately by mixing and/or heating the aluminum halide with extraneous hydrocarbons, may be employed for the alkylation reaction.

In the alkylation, the temperature required within the range of -65 to -15° C. for optimum alkylation with minimum undesirable cleavage and polymer formation varies with the catalyst, the reactivity of the aromatic and the olefin used. For example, in the presence of unpromoted aluminum chloride, optimum octylation of toluene with diisobutylene occurs at about -35 to -20° C. With benzene, however, a less reactive aromatic, optimum octylation occurs at a higher temperature, i. e. about -20 to -15° C. In the alkylation of benzene, the benzene is advantageously dissolved in a solvent such as n-pentane or n-heptane to maintain solution. When the hydrogen halide addition product of the olefin is used for alkylation, generally lower temperatures are required. For example, t-dodecylchloride and toluene give high yields of dodecyl-toluene, and t-hexadecyl chloride and toluene give high yields of octyl-toluene, but a temperature of about -60 to -35° C. is required for optimum results. The catalysts may produce select cleavage of higher molecular weight olefins in that good yields of octylated aromatics can be obtained from C₁₆ olefins such as tetraisobutylene.

When aluminum halide catalysts promoted with a hydrogen halide are employed, generally lower temperatures are required for optimum alkylation without undesirable cleavage than when using an unpromoted catalyst. For example, optimum octylation of toluene with diisobutylene occurs at about -65° C. in the presence of an aluminum chloride catalyst promoted with hydrogen chloride. With benzene, however, such low temperatures are not required and optimum octylation is obtained with a temperature range of about -40 to -20° C., particularly about -35° C. The hydrogen halide addition products of the olefin may be used if desired and require similar temperatures.

The process of our invention will be further illustrated by the following examples.

Example I

A four-necked fluted flask was fitted with a stirrer, dropping funnel, thermometer and reflux condenser holding a calcium chloride drying tube. An isopropanol bath cooled with Dry Ice was used to obtain sub-zero tem-

5

peratures. Eleven grams of aluminum chloride catalyst were added at -30°C . to 460 grams of toluene in the flask and to this stirred mixture were added 112 grams of diisobutylene over a period of 170 minutes while maintaining the temperature at -30°C . Stirring was continued for 60 minutes after addition of the olefin while maintaining the temperature at -20°C . The reaction was stopped by quenching the hydrocarbon layer with water. The alkylation products were washed with water and sodium bicarbonate solution, dried over anhydrous potassium carbonate and fractionally distilled. The distilled products were examined using an infrared spectrophotometer.

The products, based on the weight percent of olefin converted, were 28.5 percent para-t-octyl and 24.5 meta-t-octyl toluene, 14.9 percent para-t-dodecyl and 5.9 percent meta-t-dodecyl toluene and only 6.1 percent t-butyl toluene. No polymer was formed.

Example II

Using the procedure of Example I, the same proportions of aluminum chloride, toluene and diisobutylene were reacted. The catalyst was added at -30°C . and the olefin was added over a period of 30 minutes and stirring was continued for 60 minutes. The reaction temperature was maintained at -34°C . The products, based on the weight percent of olefin converted, were 45.4 percent t-octyl toluene, 25.4 percent t-dodecyl toluene, 23.8 percent para-t-hexadecyl toluene and only 6.5 percent t-butyl toluene. No polymer was formed.

The para-(t-hexadecyl) toluene or 2,2,4,6,6,8-heptamethyl-4-(p-tolyl) nonane was examined to determine its physical properties. The compound had a boiling point of 200°C . at 30 mm. and was a gel at room temperature. The refractive index ($n_{25/D}$) was 1.4893 and the specific gravity ($d_{20/4}$) was 0.8730.

Example III

Using the procedure of Example I, the same proportions of aluminum chloride, toluene and diisobutylene were reacted. The catalyst was added at -35°C . and the olefin was added over a period of 34 minutes and stirring was continued for only 6 minutes. The reaction temperature was maintained at -35°C . The products, based on the weight percent olefin converted were 69.7 percent para-t-octyl and 9.9 percent meta-t-octyl toluene and only 4.7 percent para-t-butyl and 1.3 percent meta-t-butyl toluene. No polymer was formed. The high yield of t-octyl toluene shows the advantage of slow addition of the olefin with early quenching of the reaction.

The para-(t-octyl) toluene or p-(1,1,3,3-tetramethylbutyl) toluene was examined to determine its physical properties. The compound had a boiling point of 249°C . at 760 mm. and a melting point of -10°C . The refractive index ($n_{25/D}$) was 1.4939 and the specific gravity ($d_{20/4}$) was 0.8736. A molecular weight of 200, 88.1 percent carbon and 11.8 percent hydrogen were found which closely corresponds to the calculated molecular weight of 204.3, percent carbon of 88.1 and percent hydrogen of 11.9 for the formula $\text{C}_{15}\text{H}_{24}$.

Example IV

Using the procedure of Example I, 11.7 grams of aluminum chloride were added at -20°C . to 460 grams of toluene. 224 grams of tetra-isobutylene were added to the stirred mixture over a period of 60 minutes and stirring was continued for 60 minutes. The reaction temperature was maintained at -35°C . The products, based on the weight percent olefin converted, were 62.5 percent para-t-octyl, 3.9 percent meta-t-octyl and 1.4 percent octyl toluene, 10.1 percent dodecyl toluene, 16.0 percent para-hexadecyl toluene and only 4.6 percent t-butyl toluene. No polymer was formed. Thus, select cleavage of the C_{16} olefin was obtained to produce a good yield of t-octyl toluenes.

6

Example V

Using the procedure of Example I, 11.1 grams of aluminum chloride were added at -20°C . to 390 grams of benzene in 270 grams of an n-pentane diluent. 112 grams of diisobutylene were added to the stirred mixture over a period of 30 minutes and stirring was continued for 60 minutes. The reaction temperature was maintained at -20°C . The products, based on the weight percent olefin converted, were 4.1 percent t-butyl benzene, 6.0 percent t-octyl benzene and 1.0 percent di-t-octyl benzene, 16.6 percent of a C_{12} di-substituted benzene and 52.9 percent polymer.

Example VI

Using the procedure of Example I, 4.8 grams of aluminum chloride were added at -20°C . to 154 grams of toluene. 50 grams of t-octyl chloride were added to the stirred mixture over a period of 30 minutes and stirring was continued for 60 minutes. The reaction temperature was maintained at -60°C . The products, based on the weight percent alkyl chloride converted, were 16.9 percent para-t-octyl and 51.1 percent meta-t-octyl toluene and only 11.2 percent t-butyl toluene.

The meta-t-octyl toluene or m-(1,1,3,3-tetramethylbutyl) toluene was examined to determine its physical properties. The compound had a boiling point of 118°C . at 15 mm. and 242°C . at 760 mm. and was a gel at room temperature. The refractive index ($n_{25/D}$) was 1.4937.

Using the procedure of Example I, 11.5 grams of aluminum chloride were added at -20°C . to 460 grams of toluene and 3 grams of HCl was passed into the mixture. 112 grams of diisobutylene were added to the stirred mixture over a period of 50 minutes and stirring was continued for 40 minutes. The reaction temperature was maintained at -65°C . The products, based on the weight percent olefin converted, were 61.6 percent para-t-octyl and 10.9 percent meta-t-octyl toluene, 20.6 percent para-t-dodecyl and 4.1 percent meta-t-dodecyl toluene and only 3.1 percent t-butyl toluene and 2.9 percent polymer.

Example VII

Using the procedure of Example I, 5 grams of aluminum chloride were added at 0°C . to 156 grams of benzene in 120 grams of n-pentane. 81.6 grams of t-dodecyl chloride were added to the stirred mixture over a period of 100 minutes and stirring was continued for 30 minutes. The reaction temperature was maintained at -40°C . The products, based on the weight percent olefin converted, were 26.7 percent octyl benzene, 3.5 percent di-t-butyl and 25.3 percent t-dodecyl benzene.

The t-dodecyl benzene or 2,2,4,6,6-pentamethyl-4-phenyl heptane was examined to determine its physical properties. The compound had a boiling point of 297°C . at 760 mm. and was a gel at room temperature. The refractive index ($n_{25/D}$) was 1.4921 and the specific gravity ($d_{20/4}$) was 0.8693. 87.7 percent carbon and 12.7 percent hydrogen were found which closely agrees with the calculated percent carbon of 87.7 and percent hydrogen of 12.3 for the formula $\text{C}_{18}\text{H}_{30}$.

Example IX

Using the procedure of Example I, 6 grams of aluminum chloride were added at -45°C . to 39 grams of benzene in 187 grams of an n-pentane diluent. 112 grams of t-octyl chloride were added to the stirred mixture over a period of 120 minutes and stirring was continued for 10 minutes. The reaction temperature was maintained at -45°C . The products, based on the weight percent olefin converted, were 13.4 percent t-octyl benzene, 11.2 percent octyl benzene, 4.4 percent di-t-butyl benzene, 19.4 percent dodecyl benzene, 30.8 percent di-t-octyl benzene and 1.6 percent dioctyl benzene. No butyl benzene was formed.

The di-t-octyl benzene or 1,4-di-(1,1,3,3-tetramethylbutyl) benzene was examined to determine its physical properties. The compound had a boiling point of 329° C. at 760 mm. and was a gel at room temperature. The refractive index (n 25/D) was 1.4959 and the specific gravity (d 20/4) was 0.8831. A molecular weight of 297, 87.1 percent carbon and 12.4 percent hydrogen were found which closely agrees with the calculated molecular weight of 302.5, percent carbon of 87.3 and percent hydrogen of 12.7 for the formula $C_{22}H_{38}$.

Example X

Using the procedure of Example I, 12 grams of aluminum chloride were added at -30° C. to 460 grams of toluene. 168 grams of triisobutylene were added to the stirred mixture over a period of 30 minutes and stirring was continued for 60 minutes. The reaction temperature was maintained at -35° C. The products, based on the weight percent olefin converted, were 8.0 percent para-t-octyl toluene, 1.6 percent meta-t-octyl toluene, 24.3 percent para-t-dodecyl toluene or 2,2,4,6,6-pentamethyl-4-(*p*-tolyl) heptane, 2.0 percent meta-t-dodecyl toluene, 7.9 percent para-hexadecyl toluene, 39.0 percent polymer and only 12.6 percent t-butyl toluene.

We claim:

1. A process for the production of long chain tertiary alkyl substituted monocyclic aromatic hydrocarbons in which the alkyl group contains from 8 to 20 carbon atoms, which comprises reacting a monocyclic aromatic hydro-

carbon selected from the group consisting of benzene and toluene with a scission-susceptible tertiary olefin selected from the group consisting of polymers of isobutylene containing from 8 to 20 carbon atoms and their hydrogen halide addition products in the presence of a catalyst comprising aluminum chloride while controlling the temperature at about -65° to -15° C.

2. The process of claim 1 in which the monocyclic aromatic hydrocarbon is toluene.
- 10 3. The process of claim 1 in which the catalyst is aluminum chloride promoted with hydrogen chloride.
4. A process for the production of long chain tertiary alkyl substituted toluenes in which the alkyl group contains from 8 to 20 carbon atoms, which comprises reacting toluene with a polymer of isobutylene containing from 8 to 20 carbon atoms in the presence of an aluminum chloride catalyst while controlling the temperature at about -35° to -20° C.
